CLAIM

The ornamental design for a diving fishing lure, as
shown and described.

DESCRIPTION

FIG. 1 is a top plan view of a diving fishing lure showing
my design;

FIG. 2 is a rear elevational view thereof;

FIG. 3 is a left side elevational view, the right side being
a mirror image thereof;

FIG. 4 is a front elevational view thereof; and,

FIG. 5 is a perspective view thereof.

FIG. 1

FIG. 2

FIG. 3

FIG. 4
